UNITED STATES PATENT OFFICE.

JAMES G. H. BUCK, OF DALLAS, TEXAS.

RECORDING BALLOT-BOX.

SPECIFICATION forming part of Letters Patent No. 224,385, dated February 10, 1880.

Application filed October 8, 1879.

To all whom it may concern:

Be it known that I, JAMES G. H. BUCK, of the city and county of Dallas, and State of Texas, have invented a new and Improved 5 Recording Ballot-Box; and I do hereby declare that the following is a full, clear, and exact description of the same, reference being had to the accompanying drawings, forming part of this specification.

10 The object of my invention is to indicate accurately and instantly the result of an election; to prevent the possibility of rifling the box of its ballots or of stuffing it with fraudulent ones; to promote the convenience of the 15 public by determining the result of the election immediately upon closing the polls; to curtail the expenses of election by dispensing with the services of vast numbers of men and the necessity of counting the votes; to reduce 20 those sources of error and doubt which are inseparable from the old form of ballot-box and which occasion a great majority of contested elections, and to protect the voter more fully 25 against the dominating influence of designing men, as well as his privilege of secret voting.

To these ends my improvement consists in a novel organization of recording mechanism, which will now be more fully described with reference to the drawings, in which—

30 Figure 1 is a plan view of the mechanism of the ballot-box removed from the box or case, and having in this view a portion of the upper cylinder broken away to show the devices beneath. Fig. 2 is a side elevation of 35 the same parts shown in Fig. 1. Fig. 3 is an end elevation of the box, the view being taken at the end where the record appears through openings or windows in the box. Fig. 4 is a detail of the top cylinder of the device. Fig. 40 5 is a perspective view of the box with a part of the lid broken away, and showing the place for the introduction of the voting-board F.

X represents the outside casing or inclosure of the ballot-box, which has at one end an 45 opening, (see Fig. 5,) through which access is had to the mechanism within for depositing and recording the votes. This mechanism embodies an independent organization for each candidate to be voted for, arranged side by 50 side; but as all of these organizations are exactly alike, I have, for the sake of simplic-

ity, made the ballot-box narrower than it would be in practice, and have arranged only one train of mechanism therein. On a rotary shaft, E, in said box (see Figs. 1 and 2) I arrange a 55 wheel, A, being one of a set corresponding to the number of candidates. This wheel bears upon its periphery teeth from ten to one thousand, according to the number of votes to be polled, and has beside each tooth on its widened 60 periphery a corresponding number for each tooth, graduated in tens, as 10, 20, 30, 40, &c., which show successively through the opening a in the box, as seen in Fig. 3. This wheel, then, is the tens-wheel—i. e., a tooth moves one 65 space for every ten votes—and it is operated by the shaft B of the units-wheel through a worm, B'. D is the units-wheel, which is arranged upon the end of the shaft B, and is made in the form of a disk like a clock-face, 70 having a smaller series of figures thereon, from 1 to 10, all of which figures show successively through the opening b in the box. (See Fig. 3.)

For actuating these wheels by the act of 75 voting I have devised a peculiar mechanism. On the end of shaft B, opposite the units-wheel D, I place a wheel, K, having ten teeth corresponding to the numbers of the disk. When at rest the wheel is locked against turning by a stop-block, I, which slides vertically 80 on a stud, c, so that when down it passes between and locks the teeth, and when raised permits the wheel to be turned.

Before proceeding to explain more definitely 85 how these devices are acted upon, I would state that my system of voting contemplates dispensing with printed tickets and substituting therefor a system of solid ballots or counters, which are dropped into the box of 90 the candidate to be voted for; and for this purpose I make these ballots in such shape that the act of inserting them turns the recording devices heretofore described. Thus the ballots I make in the shape of metal blocks 95 H, having two cam-surfaces and a socket adapted to fit on the end of a series of rods, I, which are attached to the slide F. This slide is a detachable board, which may be lifted off from the guide-rods J, and which is put in the 100 hands of the voter. Now, these slides F being provided with a rod, L, for every candi-

date, whose name and the office for which he is running are plainly marked thereon, the voter takes the slide from the officer in charge and places upon the rods L one or more ballots, 5 H, the said ballot being fitted by its socket on the rod representing the candidate for whom he desires to vote. The voter then applies the slide to its guide-bars J and pushes it forward.

10 Now follows the peculiar action of my device: Every candidate for whom the voter wishes to cast a ballot has his rod L armed with a ballot or point, H, and the other candidates have upon their rods L no such point, 15 and when the slide is pushed forward the points or ballots on the ends thereof serve to give motion to the mechanism belonging to the selected candidate, while the mechanism belonging to the other candidate is undisturbed, for the reason that his corresponding rods L have no points, the slide F being made long enough to cover the several sets of mechanism of all the candidates. As the points H advance with the motion of the slide, the 20 cam-edge y (shown in detail) lifts the locking-stop I to allow the units-wheel to be free to turn; then immediately the cam-edge x, (shown in detail,) acting horizontally, strikes one of the teeth of the wheel K and rotates 25 the wheel-shaft and disk D one notch, thus recording one vote. As the rear end of the detachable point H passes, the stop drops back on the wheel, and then, when the slide F is drawn back again, the point H is pulled off 30 and drops into the ballot-box, constituting a counter, which supplies concomitant proof of the vote.

It will thus be seen that these points H are to be supplied in numbers, and that they serve 40 both to actuate the recording mechanism and to act by being deposited as a ballot in the fortunate candidate's compartment.

In order to act as a further check against fraud, and for the purpose of purging the box 45 of any illegal ballots, I have arranged a second recording device above the first, which is operated simultaneously with it. This consists of a cylinder, C, (see Fig. 4,) bearing a spiral strip of paper, which is divided into 50 equal spaces equal to the whole number of votes to be cast. This cylinder is arranged just above a needle, N, borne by the stop-block I, and is so arranged to move that for every vote it turns a new space to the point N, and 55 as the latter rises with block I from the action of cam-point H said needle is made to puncture the space in the strip of paper immediately above it. In order to bring new spaces successively above the needle N a step-by-step 60 motion of the cylinder, and also a longitudinal movement of the same, is required.

In supplying these movements I place upon the slide F a second cam, G, somewhat similar to H, having an incline, t, Fig. 2, in a vertical 65 plane, and an incline, s, Fig. 1, in a horizontal plane. As this cam G moves forward with the slide in the act of voting its incline t lifts

a stop, O, from off a gear-wheel, P, while its incline s strikes a tooth of the gear-wheel and rotates it one space. This gear-wheel, it will 70 be seen, is attached to a shaft, Q, carrying a worm, R, which worm engages with a worm-wheel, S, on the shaft of the cylinder C to give it a rotary step-by-step motion.

In imparting the longitudinal movement of 75 the cylinder necessitated by the pitch of the spiral folds of the strip of paper, the opposite end of the cylinder-shaft T is screw-threaded, and is made to revolve in a screw-threaded bearing.

Now, if a voter, after having voted, be found to have cast a vote without being entitled to the same, some means are required for enabling the officers in charge to determine whom that man voted for. For this purpose cylinder C is made long enough to extend above the needle-points N of all of the candidates, and a certain set of spiral rows of spaces on this cylinder is devoted to each candidate. At the end of the cylinder is placed a circular 85 row of figures, being, as shown, from 1 to 50, so that there may be one complete revolution of the cylinder for every fifty votes. There may be, however, any greater number of figures in one spiral revolution, as 1 to 100, 1 to 90 1,000, &c. Now, as each vote is, in the order 95 of voting, numbered, the act of voting brings a space of the set of spiral rows of each candidate over the needle-point, and that space will be punctured, and will be indicated at the end 100 of the cylinder in the order of voting. Thus when the twenty-fifth voter casts his ballot he makes a puncture on a horizontal line with the figure 25 at the end of the cylinder and in the set of spiral spaces belonging to the candidate 105 whose needle-point is moved. Now, if after the election it be found that voter No. 25 (whose name is entered by the clerk opposite his number in the book of registration) was an illegal voter, it becomes an easy matter for 110 the officers in charge to determine which candidate voter 25 cast his ballot for. Thus, referring to figure 25 at the end of the cylinder and tracing the horizontal spaces, if it be found that candidate No. 1 has no puncture in 115 his space No. 25, and candidate No. 2 has, then it shows conclusively that voter 25 cast his ballot for candidate No. 2, and the ballot-box is purged by taking one vote from his amount.

In making use of my invention I do not confine it simply to its use as a ballot-box, but may employ the same principle in recording fares, games, or other registrations.

Having thus described my invention, what 125 I claim as new is—

1. The point H, having the two cam-edges x and y in different planes, combined with the wheel K and locking-slide I, and adapted to lift the said locking-slide with one cam-edge 130 and turn the wheel with the other, substantially as described, and for the purpose herein set forth.

2. In a ballot-box or recording device, the

combination, with the graduated wheels, of a stop device locking one of said wheels and a slide or carriage bearing a detachable point or end piece, which point or piece is adapted to lift the stop, rotate the wheel, and then be deposited as a ballot, as and for the purpose set forth.

3. The combination, with a set of guides, J, and the recording mechanism, of a removable sliding board, F, carrying stem L, representing the different candidates, together with a set of detachable points, H, adapted to fit on said stem and operate upon the recording device, as described.

4. The combination of a recording device 15 provided with numbers, a detachable balloting device adapted to operate said recording device and be then deposited in the box, and a check-cylinder operated by the movement of the balloting device to check the ballots by a 20 series of marks or punctures, as set forth.
